Electric Appliance Corporation, Toledo, Ohio,
a corporation of Delaware

Application July 27, 1936, Serial No. 92,712

5 Claims. (Cl. 15—6)

This invention relates to suction cleaners of the type employing a revolving agitator equipped with brushing or beater elements or both, for operating upon a suspended section of carpet, and has as its object to decrease the beating noise which is necessarily produced by such a cleaner.

The modern tendency in vacuum cleaners is toward more powerful cleansing ability. To achieve this it is necessary from a practical standpoint, to increase the power of beating. A certain amount of increased dirt-getting ability may be also obtained by increasing suction, but beating is the most essential factor, especially since the room for improvement lies in the ability to extract embedded dirt, the surface cleaning efficiency of most cleaners already being at a high stage of perfection.

This trend has emphasized the problem of quietness of operation. This problem is coped with in one instance by double opposed helical arrangement of the beaters such that the beaters tend to ride against the carpet continuously. The type of beater contemplated by the present invention, however, is one that strikes the carpet suddenly and all at once, giving a truer beating effect and much greater dirt loosening efficiency per lineal unit of beater length. The problem of noise is magnified in dealing with such a beater and the present invention aims to minimize the noise without prejudice to this type of beater design.

Another element contributing to the magnification of the problem in connection with the present invention is the fact that it was considered essential in increasing power, not to increase the weight of the machine, and in order to achieve this, certain parts, such as motor housing, fan housing, and part of the suction chamber, are made of stamped and drawn sheet metal.

The drumming sound occasioned by beating, is due partly to vibrations set up in the carpet directly by the beater blow, partly by the periodic striking of the carpet against the suction chamber, and partly by transmission of the jar back through the spindle and its bearings into the walls of the suction chamber and attached parts. The latter phase is aggravated by the use of ball bearings, which in itself is highly desirable.

The present invention greatly decreases the noise by isolating the rotary agitator from metal to metal connection with the rest of the cleaner, thereby largely cutting off the transmission of jar through the spindle to the suction chamber.

At the same time, it decreases the severity of the blows delivered by the beaters, thereby decreasing carpet injury beyond what is accomplished by the resiliency of mounting of the beater elements, and further decreases noise by dampening noise producing carpet vibrations.

The present invention further decreases carpet vibration noise by providing a carpet engaging shoe or shoes adapted to bear the brunt of carpet impact against the suction mouth, and to dampen vibrations thereby produced. To this end, the shoes are cushion-mounted and isolated from metal to metal contact with the suction chamber walls.

Further objects will appear in the perusal of the following detailed description of the invention in connection with the accompanying drawings in which:

Fig. 1 is a side elevation of a vacuum cleaner embodying the invention,

Fig. 2 is an inverted plan view of the floor tool thereof,

Fig. 3 is a cross section through the same taken on the line 3—3 of Fig. 2,

Fig. 4 is a longitudinal sectional view through one end of the floor tool,

Fig. 5 is an end elevation of one of the carpet engaging shoes,

Fig. 6 is an end elevation of one of the agitator mounting cushions,

Fig. 7 is an inverted plan view of a floor tool embodying a modification of the invention,

Fig. 8 is a transverse sectional view of the same taken on the line 8—8 of Fig. 7,

Fig. 9 is a longitudinal sectional view of the same, the agitator and its mounting being shown in elevation,

Fig. 10 is a detail longitudinal sectional view of one end of the floor tool,

Fig. 11 is a similar view of a modification of the invention,

Fig. 12 is a similar view of another modification of the invention,

Fig. 13 is a similar view of another modification of the invention,

Fig. 14 is a similar view of another modification of the invention, and

Fig. 15 is a sectional view taken on the line 15—15 of Fig. 11.

The type of vacuum cleaner in which the present invention is embodied is disclosed more in detail in my pending application, Serial Number 74,012, filed April 13, 1936, now Patent 2,168,899. In such a cleaner the floor tool includes a suction chamber A having an agitator chamber 10 pro-

vided with a mouth 11 and an agitator 12 therein; a fan case 13 has an inlet or opposed inlets in pivotal relationship to an elbow or elbows 14 attached to the suction chamber A; the handle 15 is rigidly secured to the fan case 13; and the fan and agitator are driven by a motor 16 through the medium of belts 17 and 18 respectively.

The fan case 13 and casing 19 which covers the motor 16 are preferably of stamped and drawn sheet metal, and the bottom of the suction chamber A comprises a removable plate 20 (Fig. 2) which also is of stamped sheet metal.

In the operation of the cleaner the carpet is drawn up to the mouth 11 and is beaten by the beater bars 21 (Fig. 8) resiliently mounted on the spindle 22 of the agitator 12 by means of soft rubber mountings 23. Brushing elements 24 mounted in the spindle 22 brush away the dirt that is loosened by the beaters 21.

According to the present invention, the spindle 22 may be mounted on a through shaft 25 (Fig. 4) or stub shafts 25a (Fig. 12) and provided with bushing bearings 26 (Fig. 4) or ball bearings 26a (Fig. 12) by means of which the spindle is rotatably mounted in the suction chamber A. In the form of the invention shown in Fig. 4, the shaft 25 is stationary and has a projecting end portion 27 extending through the cap portion 28 of the carpet engaging shoe 29 and secured thereto by a nut 30.

The nut 30 is adapted to be recessed in a downwardly opening recess 31 in the soft rubber cushion 32, and releasably supported in the upper end region thereof by the shouldered regions 33 of the metal clip 34 lining the recess 31 and vulcanized to the rubber. The clip 34 may or may not be of spring metal, if not the rubber which backs it up will give it added resiliency over its inherent resiliency.

To the opposite face of the cushion 32 is vulcanized a back plate 35 which is attached to the end wall 36 of the agitator chamber 10 by means of screws 37. The upper region of the plate 35 is bent forwardly at 38 to provide support for the rubber to prevent undue recession of the rotary agitator upwardly under working conditions.

The shoe 29 is provided with the carpet engaging plates 39 of stainless steel spot welded or riveted to the bottom flange 40 of the shoe. Formed integrally with the flange 40 are a pair of ears 41 projecting upwardly and adapted to snugly engage in the lower region of the recess 31 of the cushion.

It will now be seen that the rotary agitator and the carpet engaging shoes are supported in the suction chamber by the engagement of the projecting portions of the shaft 25 in the recess 31. The rotary agitator and shoes may be removed as a single unit.

The carpet engaging plate 39 is spaced on all sides from the walls of the suction chamber and insulated from any metal to metal contact with any part of the suction chamber. The sides of the mouth may be defined between stainless steel lips L secured to the walls of the agitator chamber 10.

The bearing assembly in Fig. 4 includes the bearing bushings 26 of porous metal material such as "Oilite" rotatably mounted on the trunnion sleeves 41a secured on the shaft 25, and the mounting rings 42 connect the bushings 26 to the spindle 22, and provided with annular oil grooves 43 filled with oil packing and providing

a source of replenishment of the oil in the bushings 26.

In the form shown in Fig. 7, the carpet engaging shoes are formed in a single mouth frame 44 having the end portions 39a and an intermediate bridge bar 45 which lies directly beneath the belt 18. A series of carpet spacing bars 46 are secured to the frame 44 and extend across the mouth 11 at properly spaced intervals.

The mouth frame 44 is received between the front and rear walls of the agitator chamber 10, and is spaced therefrom around its entire periphery. It is rigidly attached to the bracket portions 29 which include the cap portions 28 in which the ends of the spindle 22 are rotatably received. The end portions of the shaft 25 are mounted in the cushion 32 in the same manner as described for Fig. 4.

In the form shown in Fig. 11, the cushion instead of being attached to the end wall of the agitator chamber is loosely received in a semi-circular socket 48 therein and held by spring clips 47 secured thereto. The cushion in this case is circular in form and embodies a ring-shaped body of rubber 49 vulcanized between the spindle cap 50 and the end cap 51. The latter serves as the means for engaging the socket 48. The spindle cap 50 has a central sleeve 52 receiving the end of the shaft 25.

In the form shown in Fig. 12, instead of the through shaft 25 there is the stub shaft 25a which is secured to the end wall 53 of the spindle, and mounted in the inner race of the ball bearing 26a the outer race of which is mounted in the spindle end cap 50a. The resilient mounting in this case is practically the same as that described for Fig. 11, including the end cap 51 and body of rubber 49.

In the form shown in Fig. 13, the through shaft 25 is mounted directly in the socket 48a in the agitator chamber end wall, and the spindle 22 is insulated from the shaft 25 through the medium of the resilient mounting including the ring of rubber 49a vulcanized between the end cap 51a and the inner sleeve 52. The latter receives the inner race of the ball bearing 26a and the outer race thereof is mounted in the spindle 22. The spindle cap 51 has a hub portion 53 which is mounted on the shaft 25.

In the form shown in Fig. 14, this through shaft 25 is again mounted in the socket 48a in the end wall of the agitator chamber, and the ball bearing 26a is in this case mounted directly on the shaft 25 through the medium of the hub portion 53 of the spindle cap 51, the outer race of the bearing being connected to the spindle 22 through the medium of the resilient mounting including the inner sleeve 52a, the soft rubber ring 49a, and the outer ring 51b vulcanized to the rubber ring.

The invention provides a resilient vibration absorbing cushioning material interposed between the rotary agitator and the suction chamber in which it operates. Although this cushioning device may be interposed between the shaft and the hollow spindle as in Figs. 13 and 14, it is preferably interposed between the projecting shaft members and the end walls of the suction chamber as in Figs. 4, 10, 11, and 12.

This cushioning medium prevents the transmission of sound vibrations from the agitator spindle to the suction chamber or any other portion of the machine, and tends to dampen sound vibration set-up in the carpet itself, owing to the increased resiliency of the beating which results from its employment.

The invention further provides a carpet engaging shoe or shoes which bear the brunt or all of the impact of the carpet against the suction chamber mouth as the carpet is sucked back against the mouth after the passage of a beater. This slapping of the carpet against the suction chamber mouth which otherwise is amplified in the metal walls of the suction chamber, is largely damped by the cushion mounting shoe or shoes.

Attention is called to the fact that the shoe or shoes are curved downwardly so as to give a sled-runner-riding effect on the carpet and to more effectively hold the carpet against being drawn too tightly into the suction chamber at the end regions thereof.

The total ultimate result is provision of a cleaner having the desired features of improved power without increased weight, in combination with the desired quietness of operation, a result which at first seemed very difficult of accomplishment.

I claim as my invention:

1. In a vacuum cleaner, a suction chamber, a motor driven rotary agitator therein, means on which said agitator is mounted for rotation, said means comprising shaft portions at the respective ends of the agitator, and vibration absorbing cushions secured to the respective end walls of the suction chamber and comprising substantially rectangularly shaped flat blocks of rubber secured to the vertical end walls of the chamber, said cushions each having a downwardly opening recess in which a corresponding shaft portion is releasably received and supported and a spring steel liner in each of said recesses and secured to said blocks.

2. In a vacuum cleaner, a suction chamber, a motor driven rotary agitator therein, means on which said agitator is mounted for rotation, said means comprising shaft portions at the respective ends of the agitator, vibration absorbing cushions secured to the respective end walls of the suction chamber, each cushion comprising a flat substantially rectangular shaped block of rubber attached to the vertical end wall of the chamber, a metal plate vulcanized to one side of said block and forming the attachment to the suction chamber wall, a downwardly opening recess in the

other side of the block, and an inverted U-shaped metal clip vulcanized in said recess and releasably receiving and supporting a corresponding shaft portion of said agitator.

3. In a vacuum cleaner, a suction chamber, a motor driven rotary agitator therein, means on which said agitator is mounted for rotation, said means comprising shaft portions at the respective ends of the agitator, and vibration absorbing cushions secured to the respective end walls of the suction chamber, said cushions being substantially rectangular blocks of rubber, said cushions each having a downwardly opening recess in which a corresponding shaft portion is releasably received and supported, a spring steel liner in said recess the agitator at each end having a non-rotatable cap in which the end of the agitator spindle revolves, said cap being in abutting contact with the adjoining face of its respective cushion and with the spring steel liner in said recess.

4. In a vacuum cleaner, a suction chamber, a motor driven rotary agitator therein, means on which said agitator is mounted for rotation, vibration absorbing cushions interposed between said means and the respective ends of the suction chamber, and carpet engaging shoes also supported by said cushions, said shoes lying adjacent but out of contact with the respective end walls of the suction chamber and defining the end limits of the suction mouth of said chamber, said suction mouth adapted to receive and hold a portion of the carpet over which it is passing to be acted upon by the agitator.

5. In a vacuum cleaner, a suction chamber, a motor driven rotary agitator therein, means on which said agitator is mounted for rotation, and carpet engaging shoes attached to said means, said shoes including cap portions receiving the respective ends of the agitator spindle, said shoes lying adjacent but out of contact with the respective end walls of the suction chamber and defining the end limits of the suction chamber mouth, said suction mouth adapted to receive and hold a portion of the carpet over which it is passing to be acted upon by the agitator.

DEWEY M. DOW.
